Patented Feb. 3, 1976

238,625

THONG SANDAL

Harold D. York, Jr., 3952 Bluff St.,
Torrance, Calif. 90505

Filed Nov. 14, 1974, Ser. No. 523,583

Term of patent 14 years

Int. Cl. D2—04

U.S. Cl. D2—270

Fig. 1.

Fig. 2.

Fig. 3.

Fig. 4.

Fig. 6.

Fig. 5.

Fig. 7.

FIG. 1 is a right front perspective view of a thong sandal showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and

FIG. 7 is a rear elevational view thereof.

I claim:

The ornamental design for a thong sandal, substantially as shown.
